UNITED STATES PATENT OFFICE.

GOTTFRIED H. WENDE, OF BUFFALO, NEW YORK.

CURRENT MOTOR.

Application filed April 17, 1922. Serial No. 553,991.

To all whom it may concern:

Be it known that I, GOTTFRIED H. WENDE, a citizen of the United States, residing at Buffalo, in the county of Erie and State of New York, have invented new and useful Improvements in Current Motors, of which the following is a specification.

This invention relates to a motor which is operated by the current of a stream or other moving fluid, such as gas or air, and more particularly to the type having feathering blades or paddles.

Its object is to improve the means for automatically turning the paddles into their effective or operative positions with a view of rendering the same simple and strong in construction and reliable in action.

In the accompanying drawings: Figure 1 is a side elevation of a current motor embodying my improvements. Figure 2 is a top plan view thereof. Figure 3 is a fragmentary vertical longitudinal section on line 3—3, Fig. 2. Figure 4 is a perspective view of one of the blades or paddles.

Similar characters of reference indicate corresponding parts throughout the several views.

The working parts of the motor may be supported on a frame of any suitable construction, that shown in the drawings consisting of longitudinal side rails 10, 10, and front and rear legs 11, 12.

13, 13 indicate a pair of spaced belts or endless sprocket chains disposed side by side between the side rails 10. These chains pass around front and rear sprocket wheels 14 and 15, respectively, which are mounted on transverse shafts 16 and 17 journaled at their ends in suitable bearings mounted in said side rails. Disposed between these chains and pivoted thereto are a plurality of blades or paddles 18 which are adapted to fold in the plane of the chains or current when traveling against the latter and which are adapted to be projected or unfolded to a plane substantially at right angles to the chains or current when traveling in the opposite direction in which position they are presented squarely to the current for the purpose of driving the motor, in an obvious manner.

As shown in Figs. 1 and 3, these paddles are preferably located at equidistant intervals along the sprocket chains 13 and are hinged thereto to swing in a vertical plane. The paddles are preferably of such a length

that when traveling along the upper or return stretches of the sprocket chains their free edges overlap the hinged edges of succeeding paddles so as to pass edgewise through the water or other motive fluid and offer a minimum resistance. As the paddles pass from the upper stretches of the chains around the rear sprocket wheel 15 to the advancing lower stretches thereof, they are automatically and positively unfolded to their projecting position, preferably by the following means:

The knuckle or pivoted edge 18^a of each paddle is provided with a pair of arms 19 which extend substantially at right angles to the plane of the paddle. Carried by one or both of the rear sprocket wheels 15 and arranged in the path of movement of one or both series of paddle arms 19 is a paddle unfolding device which is preferably in the form of an annular flange 20 located on the inner face of said wheel and arranged substantially concentric therewith, the exterior diameter of this flange being somewhat less than the diameter of the circle describing the base line of the sprocket teeth for the purpose of forming a clearance space between said flange and the respective sprocket chain. In the folded position of the paddles, the trip arms 19 depend below the chains, so that as the paddles approach the rear sprocket wheels 15 they are successively elevated or unfolded to their operative position by the respective arms riding over the flange 20. This change of position is gradual and starts the moment the paddle arms engage the end flange and continues until the paddles reach a position substantially radially of the sprocket wheels. Further movement of each paddle in the same direction is prevented by its arms 19 abutting against the inner sides of the next succeeding paddle-knuckle, as shown in Fig. 3. By this arrangement, the paddles are automatically extended to their operative position in which they are presented broadside to the current, thus driving the shafts 16, 17, from which the motive power is transmitted to any desired machinery or apparatus.

As the paddles ascend on the front sprocket wheels, they swing by the force of the current or by gravity to the folded position shown at the upper side of Fig. 1.

In the preferred arrangement shown, the motor is arranged in a forwardly inclined position to dispose the paddles in stepped

relation, thereby presenting a maximum paddle area to the current and obtaining the highest efficiency.

I claim as my invention:

5 1. A current motor, comprising supporting wheels, an endless belt passing around said wheels, one of said wheels being provided with a laterally projecting annular flange, and a plurality of feathering paddles hinged to said belt and having trip arms arranged to engage and ride over said flange.

10 2. A current motor, comprising supporting wheels, an endless belt passing around said wheels, a paddle-unfolding device substantially concentric with one of said wheels, and feathering paddles hinged to said belt and each provided at its hinged edge with a trip arm, arranged substantially at right angles to the paddle, said trip arms being arranged to engage said paddle-un-

folding device in traveling in one direction and to overlap and abut against the inner hinged portions of the succeeding paddles in traveling in the opposite direction to prevent folding of the latter in such direction. 25

3. A current motor, comprising supporting wheels, an endless belt passing around said wheels, one of said wheels being provided with an annular flange projecting from its side, and paddles hinged to said belt and provided at their hinged edges with trip arms arranged substantially at right angles thereto, each paddle arm being arranged to engage said flange for swinging said paddles from their folded to their unfolded position in traveling in one direction and to abut against the hinged inner portions of adjoining paddles in traveling in the opposite direction. 30 35

GOTTFRIED H. WENDE.
